PLACEMENT KICKING BALL

Charles F. Ball, 1861 SW. 6th Ave.,
Pompano Beach, Fla. 33060

Filed Dec. 19, 1968, Ser. No. 15,057

Term of patent 3½ years

Int. Cl. D21—02
U.S. Cl. D34—15

Fig. 1.

Fig. 2.

Fig. 3.

FIG. 1 is a perspective view of a placement kicking ball showing my new design;

FIG. 2 is a side elevational view thereof, the rear being an identical image of the side shown; and

FIG. 3 is a top plan view thereof, a bottom plan view being identical to the image of the top shown.

I claim:

The ornamental design for a placement kicking ball, as shown.
